SOUND RECORDING APPARATUS

Isidore H. Goldman, Brooklyn, N. Y.

Application September 15, 1937, Serial No. 163,887

2 Claims. (Cl. 274—13)

This invention relates generally to devices for securing disk records to sound recording or combined sound recording and playing apparatus; but more specifically to means for securing the record disk and a driving flange to the turntable of the apparatus when used to record sound.

The main object of the invention resides in the provision of a yieldable and sensitive securing stud mounted on the turntable and adapted to engage with orifices in both the recording disk and driving flange of the sound recording apparatus.

A further object of the invention resides in the provision of a yieldable securing stud whose function is automatically suppressed when the same sound recording apparatus is used as a playback, the suppression of the function of the said securing stud being accomplished automatically by the weight of the sound record normally mounted on the turntable by the operator as if there were no securing stud affixed thereto.

A further object of the invention resides in the provision of a yieldable securing stud mounted on the turntable which requires a minimum of effort to secure therewith registration of the orifices in both the record disk and the driving flange.

These objects and other incidental ends and advantages of the invention will hereinafter appear in the progress of the disclosure and as pointed out in the appended claims.

Accompanying this specification is a drawing showing a combined sound recording and playing apparatus having a cutting head of the electromagnetic type and also a playback of the electromagnetic type to which a preferred form of the invention is especially applicable, the application however not being solely confined to sound recording and playing apparatus of the electromagnetic type. In the said drawing, corresponding reference characters designate corresponding parts throughout the several views and wherein:

Figure 1 is a top plan view of a sound recording and playing apparatus embodying a preferred form of the invention.

Figure 2 is a front elevational view of Figure 1.

Figure 3 is an enlarged fragmentary view in section showing the construction of the yieldable securing stud as applied to a record disk and a driving flange.

A sound recording and playback apparatus is now to be generally described to show the unique application of the invention thereto.

Numeral 10 designates a turntable whose motor 55 drive system is not shown, while panel 11 having

a central circular cut-out 11' for the turntable 10 supports the overhead feed mechanism for the cutting head assembly and the playback mechanism. The turntable 10 is provided with a shaft 12 passing through a bim 13 secured to the center and underside of turntable 10, the said shaft 12 carrying on its upper end a pin 14 to engage both a record disk 15 and a driving flange 16. Numeral 16 indicates the usual felt or rubber pad which is supported on the upper face of turntable 10 to furnish a friction surface for both the record disk 15 and the upper surface of the turntable 10 for the usual reasons. Numeral 17 indicates a bearing secured to the rear of panel 11 on which is pivoted by means of a pivot member 18 the overhead feed mechanism carrying the cutting head assembly.

The overhead feed mechanism comprises end blocks 19 and 20 to which are secured by means of nuts 23 upper and lower spacing rods 21 and 22, the block 19 being secured to pivot member 18. A lead screw 24 is secured between end blocks 19 and 20, the said lead screw having a cutting head carriage 25. The cutting head carriage 25 is provided rearwardly with an orifice 26 through which the upper rod 21 penetrates while intermediately of the head carriage 25 is an opening 27, the side walls of which are threaded to engage lead screw 24. The opening 27 is provided with a latch mechanism, not shown on the drawing, whereby the carriage 25 is held in and removable from threaded engagement with the lead screw 24. Forwardly of cutting head carriage 25 is secured a cutting head 28 preferably of the electromagnetic type having a stylus 29 secured thereto by means of an adjustment screw 30, the said cutting head preferably being mounted on a plate, the latter not being shown in the drawing, which pivots on the forward end of the cutting head carriage 25. Knurled knobs 31 and 32 which facilitate the insertion, removal and substitution of the lead screw 24 in tension bearings secured to end blocks 20 and 19 project from the ends of the said tension bearings, the latter being diagrammatically indicated by numerals 33 and 34.

The lead screw 24 is driven by means of a driving flange 35 having an upwardly extending shaft 36 and a top cap member 37. A gear 38 is provided on one end of the lead screw 24 and disposed within end block 20, the said gear 38 meshing with a worm gear 39 mounted on the shaft 36, the said worm gear being enclosed in a housing 38' secured to end block 20. The driving flange 35 is provided with a plurality of orifices 35

38, 40 and 41 for a purpose hereinafter to be described.

It is well known in the art that in order to cut or engrave sound records, the recording disk 6 and the driving flange operating the lead screw for the cutting head assembly must rotate with the turntable without slippage. Many means have been provided for accomplishing this result, such as the use of non-yieldable pins projecting 10 upwardly from the turntable, the said pins engaging both the driving flange and the recording disk. An apparatus embodying such integrating means is not capable of being used as a playback for any standard engraved record in view of the 15 fact that such a record may not have corresponding orifices in its body. According to the present invention, a sensitive and yieldable plunger for a turntable is provided which, in addition to serving the function of integrating the record disk 6 and the driving flange thereto, is capable of being automatically depressed by the weight of any playback record mounted on pin 14. Moreover, the sensitive and yieldable plunger herein- 20 after to be described, may be made to automatically engage one of the orifices 38, 40 and 41 of the driving flange and centrally offset orifice 50' of the record 16. With the use of the said plunger, the record disk may be placed upon pin 14 of turntable 10 so that the orifice 50' registers with 25 the yieldable plunger normally projecting above turntable 10. Likewise, driving flange 38 may be superposed on the record 16 already mounted on the turntable so that the projecting portion of the plunger engages one of the orifices 38, 40 and 41. 30 However, both the record 16 and the driving flange 38 may be separately mounted on the turntable while the latter is in motion. This is accomplished by causing slippage between the record 16 and turntable 10 until the plunger caused 35 to be depressed by the weight of record 16 registers with orifice 50' of record 16. Similarly in order that one of the orifices 38, 40 and 41 of driving flange 38 register with the plunger projecting above orifice 50' while the turntable is in 40 motion, slippage is caused between driving flange 38 and record 16 until the plunger depressed by the weight of driving flange 38 registers with any 45 one of the orifices 38, 40 and 41.

The yieldable plunger above set forth in its 50 construction and mounting is made for great sensitivity to pressure and absence of side play. The turntable 10 is provided with a centrally offset cylindrical orifice 43 in which a bearing sleeve 44 is secured. Bearing sleeve 44 is provided with 55 an upper flanged wall 45 which engages with the upper surface of turntable 10. The rubber or felt pad 15 is provided with a circular cut-out portion 15', the diameter of which is substantially equal to the diameter of the upper flanged wall 45. The bearing sleeve 44 is provided with a cylindrical bore having an upper portion 46 and a 60 lower portion of smaller diameter 47, the junction of the two bore portions 46 and 47 near the bottom of sleeve 44 affording shoulders 48. A shaft 65 49 is provided having an upper portion in the form of a plunger member 50, the diameter of the shaft 49 being substantially equal to the diameter of bore portion 47 while the diameter of the plunger member 50 is substantially equal to the diameter of bore 46. Thus, shaft 49 is provided with its 70 own bearing in the form of the inner walls of bore 47, while plunger member 50 is provided with its own bearing in the form of the inner walls of bore 46. A spring chamber is afforded within

bore 46 between shoulders 48 and the lower wall of plunger member 50, the said chamber housing an expansible helical coil spring 51 which normally causes the projection of plunger member 50 to penetrate the orifice 50' of record 16 and one of the orifices 38, 40 and 41 of the driving flange 38. Shaft 49 projects beyond the lower face of burr 13 of the turntable and is there engaged by lock nuts 51', which control the limits of the projection of plunger member 50 above turntable 10. By lowering lock nuts 51' relative to the projecting portion of shaft 49, the projection of plunger member 50 is thereby increased above turntable 10.

The weight of the record disk 16 is sufficient to 15 overcome the upward pressure of plunger member 50 caused by spring 51. The weight of the driving flange 38 is also capable of depressing the plunger member 50 when in normal upwardly projecting position.

The recording device is provided with a playback of the electromagnetic type or any other type, the said playback having a support 52 on which arms 53 and 54 are pivoted. The arm 54 has secured thereto the usual pick-up mechanism 55 having a thumb screw 56 to secure a needle 59 thereto. The playback assembly has the usual rest piece 57 and clamping member 58.

I wish it understood that minor changes and variations in the construction of the embodiment 30 of the invention relating to integration of the several parts, duplication, location, material and combinations and subcombinations thereof may all be resorted to without departing from the spirit of the invention and without departing 35 from the scope of the appended claims.

I claim:

1. In a recording apparatus for record disks having an eccentrically disposed orifice, the said recording apparatus also having an overhead feed 40 assembly with and without a playback assembly, the combination of a turntable having a centrally disposed fixed pin, a driving flange engageable with said fixed pin and being provided with a plurality of circumferential orifices, a spring operated and movable plunger carried by the turntable eccentrically of the center thereof, the spring normally forcing said plunger upwardly so that the latter projects a distance above the surface of the turntable with a force slightly less 50 than that of the weight of a record carried by said turntable and less than the weight of the driving flange, the said plunger being adapted to register with the record disk orifice and any one of the orifices of the driving flange.

2. In a recording apparatus having an overhead feed assembly the combination of a flat turntable carrying a record thereon, the said record having an eccentrically disposed opening therein, a driving flange having a flat undersurface and 60 adapted to superpose the record on the turntable and be driven by the said turntable and having eccentrically disposed engaging means thereon, a spring operated and movable plunger carried by the turntable eccentrically of the center thereof, 65 and normally projecting above the upper surface of the turntable, the said plunger engaging with the engaging means of the driving flange and the opening of the record when placed in registering relationship, the weight of either the record or 70 the said driving flange being sufficient to depress the plunger.

ISIDORE H. GOLDMAN.
